Attorney

UNITED STATES PATENT OFFICE.

HELEN FERGUSON, OF SANDWICH, ILLINOIS.

WINDOW SASH.

Application filed March 5, 1924. Serial No. 697,040.

To all whom it may concern:

Be it known that I, HELEN FERGUSON, a citizen of the United States, residing at Sandwich, in the county of De Kalb and

5 State of Illinois, have invented certain new and useful Improvements in Window Sashes, of which the following is a specification.

This invention relates to window sash structures and its consists in the novel features hereinafter described and claimed.

10 An object of the invention is to provide in a sash structure a frame hingedly connected with the frame of the sash and which carries the pane of glass. The frame may be 15 swung inwardly with relation to the sash frame whereby the exterior of the pane of glass may be cleaned at the interior of the building structure.

A further object of the invention is to 20 provide in combination with component frames hingedly connected together, sash lift devices which serve in part as means for retaining the frame elements in closed position with relation to each other.

25 In the accompanying drawing:

Figure 1 is a side elevational view of the sash.

Figure 2 is an enlarged detailed sectional view of a portion thereof cut on the line 30 2-2 of Figure 1.

Figure 3 is an enlarged fragmentary side elevational view of the sash showing the combined lift and securing device applied thereto and with the parts thereof disconnected from each other.

35 Figure 4 is a detailed transverse sectional view of the lower portion of the sash showing the combined lift and securing device applied thereto and with the parts thereof connected with each other.

The sash comprises an outer frame 1 having an inner frame 2 hingedly connected therewith by hinges 3 in a usual manner. The frame 2 carries a pane of glass 4. 45 Securing devices 5 of conventional form are carried at the free edge of the frame 2 and are adapted to engage keepers 6 mounted upon the frame 1 in a usual manner. The

securing devices 5 and the keepers 6 serve in part as means for holding the frames 1 and 50 2 in closed positions with relation to each other.

Guide plates 7 are mounted upon the lower rail of the frame 2 and each plate is provided with a horizontally disposed slot 8. 55 Studs 9 are mounted for movement along the plates 7 and pass through the slots 8 thereof. Hasp plates 10 are hingedly mounted upon the lower rail of the frame 1 and the said hasp plates are provided with T-shaped 60 slots 11, the intermediate portions of which are adapted to register with the slots 8 in the guide plates 7 when the hasp members 10 are swung up against the said plates 7. The hasp plates 10 are provided at their free 65 ends with return bend handle portions 12.

When the hasp plates 10 are swung up against the guide plates 7, the heads of the studs 9 pass through the vertically disposed portions of the T-shaped slots 11 and then 70 the said studs 9 are slipped along the slot 8 and the horizontal portion of the slot 9 whereby the heads of the studs are disposed transversely across the said slots and serve as means for connecting the hasp plates to 75 the guide plates.

When the parts of the securing devices are so connected together, the handle portions 12 of the hasp plates 10 may be freely used as gripping members for grasping the said 80 securing devices and using them as lifts for moving the sash vertically in the window frame. The window lifts are used on the lower sash only. When it is desired to clean the exterior surface of the window pane 4, 85 the securing devices 5 are disconnected from their keepers 6 and the studs 9 are moved so that their heads are opposite the vertically disposed portions of the slots 11 in the keeper plates 10. The said keeper plates 90 may then be swung down to the position shown in Figure 3 of the drawing and the frame 2 may be swung inwardly with relation to the frame 1 and consequently access 95 may be had to the exterior surface of the pane 1 for cleaning the same without neces-

situting the cleaner carrying on the cleaning operation at the exterior of the window frame.

Having described the invention, what is claimed is:

A window sash comprising inner and outer frames hinged together, a combined lift and securing device comprising a plate mounted upon the inner frame and having a slot, a stud movably mounted in the slot, a

hasp plate mounted upon the outer frame and having a T-shaped slot adapted to register with the slot in the said guide plate, the stud adapted to be passed through the T-shaped slot and slipped along the same and the hasp plate having at its free end a return bend handle portion.

In testimony whereof I affix my signature.

HELEN FERGUSON.
